R. E. Wise.

BY Victor J. Evans

ATTORNEY

WITNESS:

UNITED STATES PATENT OFFICE.

EDUARDO RAFAEL DESHON, OF CHINANDEGA, NICARAGUA, CENTRAL AMERICA.

HINGE.

Application filed March 10, 1926. Serial No. 93,756.

- This invention relates to builders' hardware, particularly to hinges, and has for its object the provision of a novel hinge provided with means whereby a door or other closure to which it is attached may be held in a selected position, this feature being of advantage inasmuch as the door may be left ajar and be prevented from blowing open or closed.
- 10 An important object is to provide a hinge having means whereby the latching device may be rendered operative or inoperative at will, depending upon circumstances or what is needed.
- 15 An additional object is to provide a device of this character which will be simple and inexpensive in manufacture, easy to install and use, positive in action, efficient and durable in service, and a general improvement 20 in the art.
- With the above and other objects and advantages in view, the invention consists in the details of construction and arrangement of parts to be hereinafter more fully described and claimed, and illustrated in the accompanying drawing in which:
- 25 Figure 1 is a view looking toward a portion of the rear edge of a door and its jamb showing the device in applied position and arranged to hold the door latched,
- 30 Figure 2 is a horizontal section taken on substantially the line 2—2 of Figure 1,
- 35 Figure 3 is a section on the line 3—3 of Figure 2,
- 40 Figure 4 is a fragmentary perspective view of the latch plate disengaged from its mounting, and
- 45 Figure 5 is a detail view of the keeper plate.
- Referring more particularly to the drawings the letter A designates a portion of a support which may be a door jamb and B designates a door or other closure mounted upon the support A by the hinge forming 50 the subject matter of this invention.
- In carrying out the invention I provide a hinge designated broadly by the numeral 10, which hinge includes leaves 11 and 12 secured respectively upon the support A and 55 closure B by any suitable means, these leaves being formed with interfitting knuckles 13 pivotally connected by a pintle pin 14. Suitably secured to or formed upon the leaf 11 is a curved ratchet arm 15 accommodated 60 within a slot 16 in the closure member B and having its upper edge formed with notches 65
17. The leaf 12 is formed with an elongated opening 18 at the upper portions of the side edges of which are beveled guides 19. Mounted within this opening is a slidable 70 latch plate 20 capable of being inserted freely within the lower portion of the opening and then slid upwardly into proper position, the side edges of this plate being grooved at 21 for accommodation of the 75 guides 19. The outer face of this plate is provided with spaced lugs 22 and 23 and its lower edge is beveled at 24 for cooperation with the notches 17 in the curved arm 15.
- The door or other closure B is recessed at 80 25 for the accomodation of a latch arm 26 which is pivotally mounted at 27 and which is formed with an elongated slot 28 within which is engaged the lug 22 on the plate 20. Secured to the leaf 12 is a leaf spring 29 en- 85 gaging over the lug 23 and acting to urge the slidable plate 20 downwardly. Secured on the door at the slot or recess 25 is a keeper plate 30 having a slot 31 therein, this keeper plate being formed with a retaining 90 shoulder 32 adapted to be engaged by the beveled lower edge of the latch 26.
- In the operation of the device, it will be apparent that if it is not desired to hold the door against movement, the latch 26 is 95 swung upwardly and sprung laterally so as to be engaged upon the retaining shoulder 32. When this is done the plate 20 is of course held in elevated position out of engagement with the curved arm 15, the spring 29 being under tension. If it is desired to 100 latch the door against movement, the latch 26 is disengaged from the shoulder 32 so that the spring 29 may operate to force the plate 20 downwardly so that the beveled lower 105 end 24 thereof will engage within a selected one of the notches 17. It is believed that the construction, operation and advantages will be readily apparent to one skilled in the art without further explanation.
- While I have shown and described the preferred embodiment of the invention, it should be understood that I reserve the right to make such changes in the form, construction and arrangement of parts as will not depart from the spirit of the invention or the scope of the subjoined claims.
- Having thus described the invention, I claim:
1. A hinge of the character described comprising a pair of pivotally connected leaves, 110 a curved arm carried by one leaf and pass-

ing through an opening in the other, said arm being notched, a plate mounted for sliding movement upon said other leaf and cooperating with said notches, and a pivoted 5 arm swingable in a plane parallel with said other leaf connected with said plate for controlling the position thereof, and keeper means engageable by said pivoted arm for holding the same stationary and consequently maintaining said plate out of engagement with the notched arm.

2. A hinge of the character described comprising a pair of pivotally connected leaves, a curved arm carried by one leaf and 15 passing through an opening in the other, said arm being notched at its upper edge, a plate mounted for sliding movement upon said other leaf and cooperating with said notches, a pivoted arm connected with said 20 plate for controlling the position thereof, and a keeper plate having a slot through which said last named arm projects and provided with a shoulder upon which the last named arm may be engaged for holding 25 the first named plate in elevated position out of engagement with the notches.

3. In a hinge of the character described, a pair of pivotally connected leaves, a curved notched arm carried by one leaf and 30 slidably through the other, a plate slidably mounted upon said other leaf for cooperation with said notches, lugs on said plate, a

spring engaging one lug for urging the plate toward said curved arm, a latch member pivoted on the second named leaf and having a slot receiving the other lug, and means for holding said latch member in elevated 35 position with said plate out of engagement with the notches.

4. A hinge of the character described 40 comprising a pair of pivotally connected leaves, a curved arm carried by one leaf, the other leaf having an opening for the passage of said arm when the leaves are relatively moved, said arm having its upper 45 edge provided with a plurality of notches, the second named leaf being provided with a vertically elongated opening provided with guides at the edges of the upper portion thereof, a keeper plate mounted within 50 said opening and having its opposite edges grooved for the reception of said guides whereby to be capable of vertical movement, spring means engaging the keeper plate for normally urging it into engagement with the 55 notched arm, a latch member pivoted upon the second named leaf, and a pivotal and slideable connection between the latch member and said plate for moving the latter vertically.

In testimony whereof I affix my signature.

EDUARDO RAFAEL DESHON.
